CHEESE SLICING MACHINE OR SIMILAR ARTICLE

John P. Mulhall, Providence, R. I., assignor to
Irving Rubin, Brookline, Mass.

Application May 6, 1949, Serial No. 2,480

Term of patent 14 years

(Cl. D55—1)

To all whom it may concern:

Be it known, that I, John P. Mulhall, a citizen of the United States of America, residing at Providence, in the county of Providence and State of Rhode Island, have invented a new, original, and ornamental Design for a Cheese Slicing Machine or Similar Article, of which the following is a specification, reference being had to the accompanying drawings, forming a part thereof.

Fig. 1 is a side elevational view of a cheese slicing machine or similar article showing my new design;

Fig. 2 is a top plan view of the cheese slicing machine shown in Fig. 1;

Fig. 3 is a side elevational view of the cheese slicing machine shown in Fig. 1 but looking at the opposite side from that of Fig. 1; and

Fig. 4 is an end elevational view of the cheese slicing machine looking from left to right at the machine shown in Fig. 1.

I claim:

The ornamental design for a cheese slicing machine or similar article, substantially as shown.

JOHN P. MULHALL.
